CLAIM

We claim the ornamental design for a control device, as
shown and described.

DESCRIPTION

[This application is a continuation of prior pending U.S.
application Ser. No. 29/515,922, filed Jan. 28, 2015; the
entirety of which is expressly incorporated by reference
herein.]

*This application is a divisional reissue of U.S. application
Ser. No. 29/695,315, which is an application for reissue of
U.S. Pat. No. D. 807,763, which issued from U.S. applica-
tion Ser. No. 29/578,733, filed Sep. 23, 2016, which is a
continuation of prior U.S. application Ser. No. 29/515,922,
filed Jan. 28, 2015, now U.S. Pat. No. 769,829, issued Oct.
25, 2016; the entireties of which are expressly incorporated
by reference herein.*

FIG. 1 is a perspective view of a control device showing our
new design.

FIG. 2 is a front view thereof.

FIG. 3 a left side view thereof.

FIG. 4 is a right side view thereof.

FIG. 5 is a top view thereof; and,

FIG. 6 is a bottom view thereof.

The rear [views] view forms no part of the design and is
omitted. The portions of the drawings appearing in *dashed*
broken lines are for environment only and do not form part
of the claimed design.

*The dot-dash broken lines illustrate boundaries which do not
form part of the claimed design.*

1 Claim, 4 Drawing Sheets

**Matter enclosed in heavy brackets [ ] appears in the
original patent but forms no part of this reissue; matter
printed in italics indicates the additions made by reissue.**
